S. BERGER,
SINK SCOOP OR SHOVEL,
APPLICATION FILED DEC. 11, 1919.

1,353,307.

Patented Sept. 21, 1920.

INVENTOR:
Samuel Berger,
BY
Graentzel and Richards,
ATTORNEYS.

UNITED STATES PATENT OFFICE.

SAMUEL BERGER, OF NEWARK, NEW JERSEY.

SINK SCOOP OR SHOVEL.

1,353,307.

Specification of Letters Patent. Patented Sept. 21, 1920.

Application filed December 11, 1919. Serial No. 344,090.

To all whom it may concern:

Be it known that I, SAMUEL BERGER, a citizen of the United States, residing at Newark, in the county of Essex and State of New Jersey, have invented certain new and useful Improvements in Sink Scoops or Shovels; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in that class of the art pertaining to household articles; and, the present invention has reference, more particularly, to a novel kitchen implement, in the form of a sink-scoop or shovel which serves the purposes of scooping up the refuse-matter which usually collects in the sink, the implement serving at the same time as a draining implement, being provided with means which readily permits the refuse-liquor and water usually scooped up with the instrument when used, to drain from the scoop, so that the drained refuse-matter can be carried to the garbage-receptacle, without any objectionable matter dripping from the scoop upon the kitchen-floor.

The present invention, therefore, has for its principal objects to provide a novel and simply constructed kitchen-utensil, in the form of a sink-scoop or shovel, in which the scoop-body and its handle are made in one piece, so as to avoid the use of rivets or other means for securing the handle to said body; and, furthermore, to provide the scoop-body with suitably arranged means which serves to readily convey the refuse-liquor and water, which may be scooped up, from said body so that only solid refuse-matter will remain upon the scoop-body, and that scooped-up matter can be carried from the sink to the garbage-receptacle, without any possibility of liquid refuse-matter dripping from the implement upon the floor.

The invention has for its further object to provide the lower surface or base of the scoop-body with depending supporting members, usually in the form of supporting ribs, whereby the main body-portions of the scoop-member, when the scoop is placed upon a surface for drainage, are raised

above such surface, to provide a suitable space for the reception of the refuse-liquor or water flowing from the perforated base-member, and for the passage of such liquor or water from beneath the scoop-body or member and resulting in the perfect and quick drainage of the solid refuse-matter.

Other objects of the present invention not at this time more particularly enumerated will be clearly understood from the following detailed description of the present invention.

With the various objects of the present invention in view, the said invention consists, primarily, in the novel sink-scoop or shovel hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claim which are appended and which form an essential part of the said specification.

The invention is clearly illustrated in the accompanying drawings, in which:—

Figure 1 is a top or plan view of a sink-scoop or shovel, showing one embodiment of the principles of the present invention; and Fig. 2 is a side elevation of the same.

Fig. 3 is a rear end view of the said scoop or shovel, looking in the direction of the arrow X in said Fig. 1; and Fig. 4 is a transverse vertical sectional representation of the said scoop or shovel, said section being taken on line 4—4 in said Fig. 1, also looking in the direction of said arrow X.

Similar characters of reference are employed in the said above described views, to indicate corresponding parts.

Referring now to the said drawings, the reference-character 1 indicates a complete sink-scoop or shovel made according to the principles of the present invention, the same comprising a main body or scoop-member 2 of the general configuration here shown, with the front edge-portion 3 of the same being usually and preferably of greater width than across the rear portion 4 of the said body or member, substantially as illustrated in Fig. 1 of the drawings. Extending rearwardly from said portion 4, as at 5, and then upwardly and angularly is a member 6, said member 6 finally extending rearwardly to form a handle 7. As shown, the

said main body or scoop-member 2 is provided at its longitudinally extending marginal edge-portions with upwardly extending side-flanges 8, the connecting spaces between said side-flanges 8 and said main body 2 being formed in a manner, so as to provide the upper surface of the said main body 2, contiguous with the said side-flanges 8, with marginal depressions or grooves, as 8, which provide suitable draining channels or ducts, as will be clearly evident. These parts of the said main body or scoop-member 2, as will be seen from an inspection of Figs. 3 and 4 of the drawings, provide suitable downwardly extending supporting elements or ribs, as 10, which while providing reinforcing members, also produce suitable supporting members acting to slightly raise the lower surface of the main body or member 2, when the scoop is placed in the sink or upon a drain-board, above the surface of the said sink or drain-board, as will be clearly evident. The said main body or member 2 may also be provided, if desired, 25 with suitably placed drip-openings or perforations 11. As shown, the member 6 and handle 7 are preferably provided with a marginal rib-like projection 12, the end-portions 13 thereof extending over the part 30 5 and for a distance upon the upper surface of the said main body or member 2, so as to provide the said channels or grooves 9 with proper discharge-ducts 14 at the rear ends of the respective channels or grooves 9, as will 35 be more clearly understood from an inspection of said Fig. 1 of the drawings. If desired, the scoop or shovel may be provided with an upwardly projecting reinforcing rib 15 which extends longitudinal and centrally 40 along the main body-member 2, the members 5 and 6, and also along the handle 7. At its end-portion the said handle 7 may be provided with a perforation 16 for the suspension of the implement from a hook or 45 nail.

From the foregoing description it will be clearly seen, that I have produced a neat and simple construction of sink-scoop or shovel, which is easily made in a single 50 piece, and which, when used for scooping up any refuse-matter, such as usually lodges in a sink, can be used, by placing the same by means of its supporting ribs 10 upon the flat sink-surface or upon the usual drain-board, as a draining means, the refuse-liquor or water that may be scooped up, draining off along the channels or ducts 9, or through the perforations 11 in the elevated body-member 2, or by means of both said channels and perforations, as the case may be.

Of course I am aware that the invention is susceptible to some changes in the construction of the implement, without departing from the scope of the invention, as set forth in the foregoing specification. Hence,

I do not limit my present invention to the exact arrangement and combination of the various parts as described in the said specification, nor do I confine myself to the exact details of the construction of the said parts, 70 as illustrated in the accompanying drawings.

I claim:

1. A scoop or shovel of the character specified, comprising a main body providing a scoop-member, a handle connected with and extending from said body, said body being provided in its upper surface with drainage-channels, said channels having rearwardly extending discharge-ends. 75

2. A scoop or shovel of the character specified, comprising a main body providing a scoop-member, a handle connected with and extending from said body, said body being provided in its upper surface with drainage channels, and the said handle being provided upon its upper surface with a marginal rib having its respective free end-portions terminating upon the upper surface of said body contiguous to the ends of 80 the respective channels.

3. A scoop or shovel of the character specified, comprising a main body having longitudinally extending and upwardly projecting marginal side-flanges, a handle connected with and extending from said body, said body being further provided in its upper surface with drainage-channels contiguous to said side-flanges said channels having rearwardly extending discharge-ends. 95

4. A scoop or shovel of the character specified, comprising a main body having longitudinally extending and upwardly projecting marginal side-flanges, a handle connected with and extending from said body, said body being further provided in its upper surface with drainage-channels contiguous to said side-flanges, and the said handle being provided upon its upper surface with a marginal rib having its respective free end-portions terminating upon the upper surface of said body contiguous to the ends of the respective channels. 100

5. The herein-described sink-scoop or shovel comprising a main body having longitudinally extending and upwardly projecting marginal side-flanges, a handle connected with and extending from said body, said body being further provided in its upper surface with drainage-channels contiguous to said side-flanges, said channels having rearwardly extending discharge-ends, and supporting ribs projecting from the lower surface of said body for elevating the latter above a supporting surface. 115

6. The herein-described sink-scoop or shovel comprising a main body having longitudinally extending and upwardly projecting marginal side-flanges, a handle connected with and extending from said body, said 120

body being further provided in its upper surface with drainage-channels contiguous to said side-flanges, supporting ribs projecting from the lower surface of said body 5 for elevating the latter above a supporting surface, and the said handle being provided upon its upper surface with a marginal rib having its respective free end-portions terminating upon the upper surface of said body contiguous to the ends of the respective channels.

In testimony, that I claim the invention set forth above I have hereunto set my hand this 20th day of November 1919.

SAMUEL BERGER.
